ELECTRON DISCHARGE AMPLIFIER

Donald E. Maxwell, Scotia, N. Y., assignor to
General Electric Company, a corporation of
New York

Application December 31, 1941, Serial No. 425,111

10 Claims. (Cl. 179—171)

My invention relates to electron discharge amplifiers and particularly to such amplifiers employing degeneration. The advantages resulting from the use of degeneration in amplifiers to reduce distortion are well known.

An object of my invention is to provide, in such amplifiers, which are required to have a definite anode impedance, means whereby degenerative voltage may be supplied to the input of such amplifiers without affecting such anode impedance. Such means adapts the amplifier to use in circuits where definite predetermined relationships between the amplifier anode impedance and other circuit impedances are important. An object of my invention is to provide means whereby degeneration may be employed in such an amplifier without affecting such impedance relationships and at the same time increasing the undistorted power which the amplifier supplies to its load circuit.

Degenerative voltage proportional either to the output voltage or to the output current of the amplifier may be supplied to the input thereof. If it be proportional to the output voltage, such voltage has the effect of decreasing the output impedance of the amplifier. If it be proportional to output current of the amplifier, it has the effect of increasing the output impedance of the amplifier. An object of my invention is to supply to the input of the amplifier two components of degenerative voltage, one proportional to output voltage and the other proportional to output current, said components being so proportioned that the output impedance of the amplifier remains at the value existing in the absence of any feedback. In this way it has been found that the undistorted power supplied to the load circuit may be very greatly increased while the circuit impedance relationships remain fixed and unaffected by such degeneration.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawing in which Fig. 1 represents a circuit in which my invention finds utility. Fig. 2 represents one embodiment of my invention and Fig. 3 is a schematic representation of the circuit of Fig. 2 to facilitate analysis.

Referring to Fig. 1, I have shown therein at 1, 2, 3 and 4 a plurality of sources of signal electro-

motive force to be amplified. These sources may comprise microphones, for example, such as are used in the studios of a radio broadcasting station. Each of these sources supplies signal electromotive force to a corresponding amplifier 5, 6, 7, 8, each of which supplies its output through a respective attenuator 9, 10, 11, 12 and impedance matching network 13, 14, 15, 16, each of which may comprise a simple resistance, to a common line 17. This line may also include an impedance matching network 18 and an attenuator 19 through which the signal electromotive forces are supplied with desired intensity to any suitable apparatus 20. This apparatus may comprise the 15 modulation system of a broadcast transmitter.

In such a system the attenuators 9, 10, 11, 12 and 19, which are arranged to control manually the intensity of signal voltage supplied therethrough, are provided with a control member, 20 which may be manipulated by the operator, and which cooperates with a calibrated scale. Such a control member is represented by the arrow 21 which is shown as cooperating with a scale 22, for example.

25 It is necessary that the calibration of these control members be accurate and the accuracy thereof is dependent on the impedance matching which exists in the circuit on either side of the attenuator. That is, the calibration of these attenuators is dependent upon the use of the attenuator between an input circuit having an impedance, which matches the input impedance of the attenuator, and an output circuit which has an impedance, which matches the output impedance 30 of the attenuator. If these impedances do not exist, then the calibration of the attenuator is inaccurate. This, of course, means that the impedance of the amplifiers 5, 6, 7 and 8, which feed the attenuators 9, 10, 11 and 12 respectively, must have an impedance which 35 matches the input impedance of the respective attenuators. If it does not match the input impedance of the attenuator, not only is the calibration of respective attenuator inaccurate, but the 40 impedance looking from the junction point 23 toward the respective attenuator is such that it does not match the impedance of the other attenuators 10, 11, 12 and 19 in parallel, with the result that the calibration of these other attenuators is also disturbed, and the impedances thereof do not match that of the respective amplifiers.

45 Thus the adjustment of any attenuator affects the gain, not only of the channel in which it is connected, but also of every other channel thereby requiring readjustment of all of the other at- 50 55

tenuators. This effect is most pronounced when the attenuator is adjusted near the position for minimum attenuation. This effect is, of course, objectionable. It is desirable that the adjustment of all of the attenuators be entirely independent of each other.

Therefore, it is necessary that the output impedance of each amplifier match the input impedance of the respective attenuator into which it operates. If the amplifier employ a discharge device having a transformer connected between its output and the input of the attenuator then the output impedance of the discharge device must match the impedance of the attenuator as seen through the transformer. This, of course, assumes a perfect transformer, a condition which obtains within practical limits of accuracy. It is desirable that the amplifiers represented by the rectangles 5, 6, 7, and 8 employ degenerative feed-back to reduce distortion and to secure certain other advantages. As commonly employed, such degenerative feed-back either reduces or increases the internal impedance of the amplifier with respect to the impedance that exists when no feed-back is present.

In accordance with my invention, a feed-back circuit is provided which secures the advantages common to degenerative feed-back systems in general, and which at the same time does not affect the internal output impedance of the amplifier.

One circuit which may be employed in accordance with my invention is shown in Fig. 2. The circuit comprises a pair of electron discharge amplifiers 25 and 26. The electron discharge amplifier 25 is supplied with voltage to be amplified through a transformer 24, the secondary of which is connected between the control electrode and cathode thereof through a bias resistor 27, which is shunted for currents of the frequency to be amplified by a condenser 28. The amplified electromotive force appears upon the anode of this device and upon the resistance 29 and is thus supplied through condenser 30 to the control electrode of the discharge device 26. Discharge device 26 operates to amplify these signal electromotive forces and to supply them through transformer 31 to the output circuit.

Anode operating potential may be supplied from a source which may be connected between ground and the terminal 32, this current being supplied to the anode of discharge device 26 through resistance 33 and the primary winding of transformer 31, and to the anode of discharge device 25 through resistances 34 and 29. It may also be supplied to the screen grid 35' of discharge device 25 through a resistance 35. The resistance 34 cooperates with condenser 34' and resistance 33 with condenser 33' to form the usual anode isolation filters commonly employed in such circuits to prevent coupling between the amplifiers through the power supply source. The screen grid 35' is connected to the cathode through a large by-pass condenser 36 having negligible impedance at any frequency to be amplified. This device 25 is also provided with a suppressor grid 37 which is connected to the cathode thereof directly. Device 25 has a high anode impedance such that it operates as a constant current source of signal voltage for the discharge device 26. That is, signal current flowing in the space path of device 25 is not affected to any material degree by the external impedance connected between the anode and cathode thereof.

The cathode of discharge device 26 is connected to ground through a resistance 40, which is in series with a resistance 41, the latter of which is by-passed for currents of the signal frequency by condenser 42. The resistances 40 and 41 are proportioned to provide a suitable operating bias upon the control electrode of the discharge device 26. The control electrode 47 is connected to ground through a resistance 43. Resistance 40, unlike resistance 41, is not bypassed and thus the signal current flowing through it produces a certain amount of electromotive force, which is impressed between the control electrode and the cathode of the discharge device in degenerative phase. This electromotive force is proportional to the signal current flowing between the anode and cathode of the discharge device.

A second component of voltage from the anode 20 of the discharge device 26 is supplied to the grid thereof through a blocking condenser 44, which is connected between the anodes of the two discharge devices through a properly proportioned resistor 45. Thus the voltage supplied from the anode of discharge device 26 through condenser 44 and resistance 45, appearing upon resistance 29, is supplied through condenser 30 to the control electrode of the device 26 in degenerative phase. This voltage is proportional 25 to the signal voltage existing between the anode of discharge device 26 and ground.

The secondary winding of the transformer 31 is connected to the load impedance which, in the equipment of Fig. 1, may be the input terminals of the attenuators 9-12. It is necessary that the internal impedance of the discharge device 26 as reflected by the transformer 31 to the attenuator match the impedance of the attenuator. Accordingly, it is requisite to satisfactory operation of the system that the degenerative feed-back employed be so controlled that it does not affect the anode impedance.

In accordance with my invention the two components of degenerative voltage supplied to the input of the amplifier are so proportioned relative to each other, to the amplification of the amplifier, and to the anode impedance thereof that they have no effect upon that anode impedance.

In order better to explain the operation of my invention, I have represented in a more schematic way in Fig. 3 the circuit which is illustrated in Fig. 2. In this circuit I have shown at 46 and 47 the cathode and control electrode of the discharge device 26. This control electrode 47 is represented as connected to the cathode through resistances R_1 and R_2 . The resistance R_1 may be considered to represent the resistance of the paths comprising the resistances 43 and 29 and the anode-cathode path of discharge device 26 of Fig. 2, all in parallel. The resistance R_2 may represent the resistance of the resistor 40 of Fig. 2. The internal anode impedance between the anode and cathode of the discharge device 26 is represented in Fig. 3 at r_p and the resistance of resistor 45 of Fig. 2 is represented in Fig. 3 as R_2 . The impedance looking from the discharge device to the primary winding of the transformer 31 of Fig. 2 is represented at R in Fig. 3. This impedance, of course, is equal to the impedance of the load which is connected to the secondary winding of transformer 31 multiplied by the turns ratio of the transformer, if transformer 31 be considered

an ideal transformer and it must equal the resistance r_p .

In order to analyze the system as thus described let us introduce a search voltage E into the circuit at the point indicated by that character in Fig. 3 and write the resulting equations.

If we let V represent the resulting voltage between the control electrode and cathode of amplifier 28, then μV represents the voltage produced in the anode circuit of the amplifier, where μ represents the amplification of the amplifier, and the following relation applies:

$$\begin{aligned} \mu V &= \mu [i_2 R_1 + (i_2 - i_1) R_3] \\ &= \mu [i_2 (R_1 + R_3) - i_1 R_3] \end{aligned}$$

where i_2 represents the signal current in the circuit R_3 , r_p , R_2 , R_1 , and i_1 represents the current in the circuit R_3 , r_p , R .

Then, applying Kirchoff's laws to the circuits carrying the currents i_1 and i_2 , we obtain the following relationships:

$$\begin{aligned} (1) \quad i_2 (R_1 + R_2) + (i_2 - i_1) (r_p + R_3) + \\ \mu [i_2 (R_1 + R_3) - i_1 R_3] &= 0 \end{aligned}$$

$$\begin{aligned} (2) \quad i_1 R + (i_1 - i_2) (r_p + R_3) - \\ \mu [i_2 (R_1 + R_3) - i_1 R_3] &= E \end{aligned}$$

Grouping the terms of Equations (1) and (2) we obtain:

$$(3) \quad i_2 [R_1 + R_2 + r_p + R_3 + \mu (R_1 + R_3)] - \\ i_1 (r_p + R_3 + \mu R_3) = 0$$

$$(4) \quad -i_2 [r_p + R_3 + \mu (R_1 + R_3)] + \\ i_1 (R + r_p + R_3 + \mu R_3) = E$$

Solving for i_2

$$i_2 = i_1 \left[\frac{r_p + R_3 + \mu R_3}{R_1 + R_2 + r_p + R_3 + \mu (R_1 + R_3)} \right] = i_1 [A]$$

Let $[r_p + R_3 + \mu (R_1 + R_3)] = B$

and $(R + r_p + R_3 + \mu R_3) = C$

Then, substituting in Equation 4

$$(5) \quad -i_1 AB - i_1 C = E$$

$$i_1 = \frac{E}{-AB + C}$$

The denominator $-AB + C$ of this expression represents the total impedance across which the voltage E appears and includes the resistance R and may be called Z_t . When expanded, Expression 5 becomes:

$$(6) \quad Z_t = R + r_p + R_3 + \mu R_3 - \\ \frac{[r_p + R_3 + \mu R_3] [r_p + R_3 + \mu (R_1 + R_3)]}{R_1 + R_2 + r_p + R_3 + \mu (R_1 + R_3)}$$

Now $Z_t = Z - R$ where Z is the impedance pre-

$$Z = 15,000 + 2,200 + (20)(2,200) - \frac{[15,000 + 2,200 + (20)(2,200)]}{83,300 + 600,000 + 15,000 + 2,200 + 20(83,300 + 2,200)}$$

sented to the primary of transformer 31, and

$$(7) \quad Z = r_p + R_3 + \mu R_3 -$$

$$\frac{[r_p + R_3 + \mu R_3] [r_p + R_3 + \mu (R_1 + R_3)]}{R_1 + R_2 + r_p + R_3 + \mu (R_1 + R_3)}$$

Now, since the anode impedance r_p of the discharge device must equal the load impedance, Z must equal r_p , or

$$(8) \quad R_3 + \mu R_3 - \frac{[r_p + R_3 + \mu R_3] [r_p + R_3 + \mu (R_1 + R_3)]}{R_1 + R_2 + R_3 + r_p + \mu (R_1 + R_3)} = 0$$

This Equation 8 expresses the relationships which must exist if Z is to equal R . It is somewhat complicated and since R_1 , R_2 , and R_3 are interrelated in any arrangement producing a desired degree of feed-back it is not feasible to solve Equation 8 for R_1 , R_2 , and R_3 individually. If certain entirely practical assumptions be made, however, this equation reduces to a very simple

expression which is satisfactory for many practical purposes in the design of such circuits. This expression is:

$$(9) \quad R_3 = \frac{R_1 r_p}{R_2}$$

The assumptions which must be made to effect this simplification of the expression of the relationships between these quantities are:

- 10 (a) That μ is very much greater than 1
- (b) That R_3 is very much smaller than R_1
- (c) That r_p is very much smaller than R_2
- (d) That r_p is very much smaller than μR_1

These conditions hold approximately true in the usual practical circuit design.

Accordingly, if the system be designed to satisfy Equation 9, the anode impedance of the discharge device will be, within a reasonable error, not greater than about ten per cent, the same as it would be if no degeneration were employed.

Moreover, as seen from Equations 6 and 7, Z is not affected by the quantity R . Accordingly, if the load impedance varies for example with frequency over the range of frequencies to be amplified, it does not affect the impedance r_p .

As a practical example, let us assume that the discharge devices 25 and 26 are of the 6J7 type. This discharge device connected as shown at 25 has an anode to cathode impedance of approximately one megohm. At 26 it is shown with its screen and suppressor grids connected directly to its anode. It thus acts as a triode and when operated with a supply voltage between ground and point 32 of 225 volts in a circuit as shown, with circuit constants presently to be given, has an anode to cathode impedance r_p of approximately 15,000 ohms and a μ of approximately 20. These circuit constants are as follows:

40	Resistance 33	ohms	10,000
	Resistance 40	do	2,220
	Resistance 41	do	570
	Resistance 43	megohms	1
	Resistance 29	ohms	100,000
	Resistance 45	do	600,000
45	Condenser 42	microfarads	40
	Condenser 44	do	.1
	Condenser 33'	do	15

Using these values, the value R_1 of Fig. 3 is

50	R ₁	ohms	63,300
	R ₂	do	600,000
	R ₃	do	2,200

Equation 7 may now be written

$$Z = 15,000 + 2,200 + (20)(2,200) - \frac{[15,000 + 2,200 + (20)(2,200)]}{83,300 + 600,000 + 15,000 + 2,200 + 20(83,300 + 2,200)}$$

$$\text{or } Z = r_p$$

This means that the impedance seen by the load circuit is not affected by the presence of the degenerative feedback voltage.

This also follows from Equation 9 which may be written:

$$2200 = \frac{(83,300)(15,000)}{600,000} \text{ approximately}$$

65 I have found that the undistorted power output of an amplifier designed in accordance with Equation 7 or 9 may be several fold greater than the undistorted power output available without negative feed-back. This result is secured without any substantial complication of the apparatus or the addition of parts which materially increase the cost thereof.

Moreover, as seen from Equation 9 the constants of the circuit may be proportioned to pro-

duce any desired amount of feed-back voltage which may be necessary to correct such distortion as may be encountered in any particular application. This contrasts, for example, to a system employing a high impedance output tube, such as a pentode, with degenerative feed-back which reduces its anode impedance to a value which matches that of its load circuit. In such an arrangement only the amount of feed-back necessary to such matching may be employed irrespective of the distortion present.

While I have shown a particular circuit designed to operate in accordance with my invention, it will be understood that this is by way of illustration of the principles involved and that many modifications may be made both in the circuit arrangement and in the instrumentalities employed and I contemplate by the appended claims to cover any such modifications as fall within the true spirit and scope of my invention.

What I claim as new and desire to secure by Letters Patent of the United States, is:

1. In combination, an electron discharge amplifier having input electrodes between which voltage to be amplified is supplied and having output electrodes between which the amplified voltage appears, a circuit between said output electrodes, means to supply voltage from said circuit to said input electrodes in degenerative phase, and means to prevent the voltage supplied by said last means from affecting the impedance between said output electrodes.

2. In combination, an electron discharge amplifier having input electrodes between which voltage to be amplified is supplied and having output electrodes between which the amplified voltage appears, a circuit between said output electrodes, means to supply voltage from said circuit to said input electrodes in degenerative phase, thereby to reduce distortion occurring in said amplifier, and means to maintain the impedance between said output electrodes in the presence of degenerative voltage supplied by said last means substantially at the value obtaining in the absence of said degenerative voltage.

3. In combination, an electron discharge amplifier having input electrodes between which voltage to be amplified is supplied and having output electrodes between which the amplified voltage appears, a load impedance connected between said output electrodes having a value equal to the output impedance of said amplifier, means to supply degenerative voltage from said output electrodes to said input electrodes thereby to increase the capacity of said amplifier to supply undistorted power to said load impedance, and means to maintain the impedance between the output electrodes of said amplifier substantially constant irrespective of the presence of said degenerative voltage.

4. In combination, an electron discharge amplifier having input electrodes between which voltage to be amplified is supplied, and output electrodes, a load circuit connected between said output electrodes, means to supply from said output electrodes to said input electrodes two voltages in degenerative phase, one of said voltages being proportional to current in said load circuit and the other of said two voltages being proportional to voltage between said output electrodes and said voltages being of such values that the internal impedance of said amplifier between said output electrodes in the presence of said voltages is of substantially the value existing in the absence of said voltages.

5. In combination, an electron discharge amplifier having an anode, a cathode, and a control electrode, a circuit between said anode and cathode including a resistance, a circuit between said grid and cathode including said resistance and a second resistance, and a third resistance connected between said anode and control electrode, said first resistance having a value substantially equal to the ratio of the product of said second resistance and the internal resistance between said anode and cathode to said third resistance.

6. In combination, an electron discharge amplifier having an anode, a cathode, and a control electrode, a circuit between said anode and cathode including a resistance, a circuit between said grid and cathode including said resistance and a second resistance, and a third resistance connected between said anode and control electrode, the values of said resistances satisfying the equation

$$R_3 + \mu R_2 - \frac{[r_p + R_2 + \mu R_3] [r_p + R_2 + \mu (R_1 + R_3)]}{R_1 + R_2 + r_p + R_2 + \mu (R_1 + R_3)} = 0$$

where R_3 represents the value of said first resistance, R_2 represents the value of said third resistance, R_1 represents the value of said second resistance, r_p represents the internal impedance between said anode and cathode in the absence of feed-back, and μ represents the amplification of said amplifier.

7. In combination, an electron discharge device having an anode, a control electrode, and a cathode, an output circuit between said anode and cathode including a resistance, an input circuit between said grid and cathode including said resistance and additional impedance, said resistance producing between said control electrode and cathode a degenerative voltage proportional to the intensity of current in said output circuit, and a resistance between said anode and control electrode to supply additional voltage proportional to the voltage between said anode and cathode in degenerative phase to said control electrode and cathode, said resistances and impedance being so proportioned that said degenerative voltages do not affect the internal anode impedance of said discharge device.

8. In combination, an electron discharge amplifier having input electrodes between which voltage to be amplified is supplied, and output electrodes between which the amplified voltage appears, the impedance of said amplifier between said output electrodes matching the impedance to which said amplified voltage is supplied in the absence of any degenerative feed-back in said amplifier, and means to produce degenerative feed-back voltage in said amplifier of proper magnitude to overcome such distortion as said amplified voltage may be subjected to and means to prevent said feed-back voltage from affecting said impedance between said output electrodes of said amplifier.

9. In combination, an electron discharge amplifier having input electrodes between which voltages of the entire range of audio frequencies are supplied, and output electrodes between which the amplified voltages appear, a load impedance connected between said output electrodes having a value equal to the output impedance of said amplifier, means to supply at least two degenerative voltages from said output electrodes to said input electrodes thereby to increase the capacity of said amplifier to supply undistorted power to said load impedance over said entire range of frequencies, one of said de-

generative voltages being proportional to the current flowing between said output electrodes and another of said degenerative voltages being proportional to the voltage between said output electrodes, and said degenerative voltages being so proportioned that the impedance between said output electrodes is maintained substantially constant irrespective of the presence of said degenerative voltages.

10. In combination, an electron discharge amplifier for voltages of a wide band of frequencies and having an anode, a cathode, and a control electrode, an input circuit for said voltages connected between said control electrode and said cathode, an output circuit connected between said anode and cathode, means connected in se-

ries with said anode and control electrode for supplying to said input circuit a degenerative voltage proportional to the intensity of current in said output circuit, means connected in shunt with said cathode and control electrode for producing in said input circuit a degenerative voltage proportional to the voltage between said anode and cathode, said degenerative voltages being of such values that the internal impedance of said amplifier between said output electrodes is of substantially the value existing in the absence of said voltages, and said voltages being effective to increase the capacity of said amplifier to supply undistorted power to said output circuit over 15 said entire band of frequencies.

DONALD E. MAXWELL.
